UNITED STATES PATENT OFFICE.

JOHN E. FARRAND, OF HOUSTON, TEXAS, ASSIGNOR TO AMERICAN ENGINEERING COMPANY, OF PHILADELPHIA, PENNSYLVANIA, A CORPORATION OF PENNSYLVANIA.

TELEMOTOR SYSTEM.

Application filed January 24, 1925. Serial No. 4,535.

My invention relates to telemotor systems, having particular relation to replenishing apparatus therefor.

One object of my invention is to provide a fluid telemotor system that shall be automatically maintained solid at all times.

Another object of my invention is to provide means, whereby the suction side of a telemotor system shall be automatically connected to a replenishing tank at every stage of the suction stroke.

A further object of my invention is to provide a telemotor system comprising a casing connected to the two sides thereof, a storage tank connected to the casing, and valves in said casing for respectively controlling the connection between the sides of said system and said storage tank, each valve being automatically operable to effect said connection upon a deficiency in its side of said system.

With these and other objects and applications in mind, my invention further consists in the details of construction and operation and arrangement, hereinafter described and claimed and illustrated in the accompanying drawings, wherein

Fig. 1 is a diagrammatic view of a telemotor system embodying my invention;

Fig. 2 is an enlarged, vertical sectional view of the operating telemotor;

Fig. 3 is an enlarged plan view of the replenishing and equalizing valve shown in Fig. 1; and

Fig. 4 is a vertical sectional view taken on the line IV—IV of Fig. 3.

A disadvantage of the telemotor systems of the prior art is in the fact that the equalization of the pressure in the different parts of the system occurs only when the steering wheel is in the mid position, and there is no provision whereby the system may be automatically replenished at every stage of the suction stroke. With such desired result in mind, the system disclosed in the several figures of the drawing was developed, and, in general, comprises an after or operated telemotor 1 of the spring centered type. This telemotor consists of cylinders 2 and 3 respectively provided with plungers 4 and 5. The latter are rigidly connected together so that when one plunger is moved into its cylinder, the other plunger is at the extreme outer limit of its stroke. The plungers 4

and 5 may be operatively associated in the usual manner with a rudder (not shown). A cross-head 6 for the plungers 4 and 5 is secured to a pair of rods 7, 7 which are slidably mounted in bearings 8 and 9, said rods being acted on by springs 11 which automatically tend to return the cross-head 6 and hence the plungers 4 and 5 to their mid position whenever they are moved therefrom.

The cylinders 2 and 3 are respectively connected by pipes 12 and 13 to port openings 14 and 15 of cylinders 16 and 17 of a forward or operating telemotor 18. The cylinders 16 and 17 are respectively provided with plungers 19 and 21 carrying racks 22 and 23 on their upper ends. A pinion 24 is so mounted intermediate the racks 22 and 23 that a movement thereof causes opposite movements of the plungers 19 and 21. The pinion 24 may be manually actuated by a steering wheel 25 through gear-wheel mechanism 26, the details of which form no part of my present invention. The relative positions of the foregoing parts are such that when the steering wheel 25 is in the mid or central position, shown in Fig. 1, the operating and operated telemotors 18 and 1 are centralized and the rudder is also in the mid position.

A valve casing 27 (Figs. 3 and 4) is provided with a longitudinally extending passage 28 terminating in port openings 29 and 31 which are respectively connected to adjacent port openings 32 and 33 (Fig. 2) of the cylinders 16 and 17. The passage 28, which connects both sides of the telemotor system, may be closed at will by means of a plug valve 34 which is mounted in the valve casing 27 intermediate the ends of the passage 28. The valve 34 is provided with a perforation 35 adapted in one position of said valve 34 to interconnect the ends of the longitudinal passage 28. The plug valve 34 may be moved into another position, wherein the perforation 35 extends transversely of the passage 28 so as to interrupt the connection between the cylinders 16 and 17 of the forward or operating telemotor 18. The upper side of the valve casing 27 is provided with a threaded cylindrical projection 36 which embraces an extension 37 of the plug valve 34. A spring 38 is disposed intermediate the extension 37 and the casing projection 36, which serves to retain the plug

valve 34 in position, the force of the spring 38 being adjusted by means of a cap 39 which is in threaded engagement with the casing projection 36 and which constitutes an abutment for the upper end of the spring 38.

As above noted, my invention further contemplates means, whereby the telemotor system may be automatically replenished at every stage of the suction stroke of the plungers 19 and 21. To this end, I provide a supply tank or chamber 41 which is connected by a pipe 42 to a chamber 43 formed in the valve casing 27. Communication between the sides of the telemotor system and the supply tank 41 may be effected through valves 44 and 45, respectively, the latter being disposed on opposite sides of the plug valve 34. The valves 44 and 45 are so designed as to be movable from their seats to connect the chamber 43 to the respective sides of the telemotor system only when a deficiency of liquid occurs or when a vacuum is formed, all as will appear more fully hereinafter. The valves 44 and 45 may be guided vertically by stems 46 and 47 which respectively extend into bores 48 of plugs 49 and 50 disposed in threaded perforations 51 in the valve casing 27. The plugs 49 and 51 further serve to permit the removal of the valves 44 and 45 should this be necessary. The aperture 35 of the plug valve 34 is connected by a passage 52 to the chamber 43, whereby the supply tank 41 may be simultaneously connected to both sides of the telemotor system when the plug valve 34 is moved to interconnect both ends of the valve passage 28.

Under conditions of operation, when the steering wheel 25 is moved from its mid position, one of the plungers of the operating telemotor, say 21, is raised and the other lowered, thereby causing fluid under pressure to be supplied to the cylinder 2 of the operated or forward telemotor 1 and a withdrawal of fluid from the other cylinder 3 thereof. The resulting movement of the cross-head 6 causes the actuation of the rudder (not shown) in the usual manner.

Should, for any reason, a deficiency of liquid occur in that portion of the telemotor system comprising the cylinder 3, the pipe 13 and the cylinder 18 or should a vacuum arise therein due to leakage, the decrease in pressure on the valve 45 causes the latter to unseat. The supply tank 41 is thus directly connected to this side of the telemotor system until the above condition has been rectified or until the plunger 21 has reached the end of its stroke. Attention is directed to the fact that the replenishing occurs automatically at every stage of the suction stroke and this is an important feature of my invention.

When the steering wheel 25 is moved in

an opposite direction, causing the plunger 21 to move downwardly, this side of the system now contains fluid under pressure and the valve 45 is forcibly retained in its seat. The other side of the system comprising the cylinder 2, the pipe 12 and the cylinder 16 is now under suction due to the upward movement of the plunger 19, and if there should be a deficiency of fluid therein, the valve 44 automatically opens to connect the supply tank 41 directly to the cylinder 16 of the operating telemotor 18. Hence both sides of the telemotor system are automatically replenished at every stage of the suction stroke of the plungers 18 and 19.

When the operating and operated telemotors 18 and 1 are out of coincidence, the steering wheel 25 is moved to the mid position and the plug valve 34 turned so as to interconnect the two ends of the valve passage 28 and hence the sides of the telemotor system. The centralizing springs 11 and 12 of the operated telemotor 1 then function to center the plungers 4 and 5 thereof. Since the aperture 35 of the plug valve 34 is also connected by the passage 52 to the chamber 43, such deficiency of fluid as may occur at this time in both sides of the telemotor system is made up.

While I have shown only one embodiment of my invention, for the purpose of describing the same and illustrating its principles of construction and operation, it is apparent that various changes and modifications may be made therein without departing from the spirit of invention, and I desire, therefore, that only such limitations shall be imposed thereon as are indicated in the appended claims or as are demanded by the prior art.

I claim:

1. A telemotor system including a valve casing connected to both sides thereof, a supply tank connected to said casing, normally closed valves respectively controlling the connection between said tank and the sides of said system, and manually operable means mounted in said casing for connecting the sides of said system at will, each of said valves being movable automatically into an open position upon a deficiency of fluid in its side of the system.

2. A system comprising two sets of telemotors, means for operatively associating the telemotors of the two sets, a valve casing connected to both sides of said system, a supply tank connected to said casing, valves in said casing automatically operable to connect the sides of said system to said tank upon a deficiency of fluid therein, and a manually operable valve in said casing for connecting the sides of said system independently of said first-mentioned valves, said manually operable valve also serving to connect said tank to the sides of said system.

3. In a telemotor system, the combination with a valve casing connected to both sides thereof, of a storage tank connected to said casing, a pair of valves in said casing respectively connecting the sides of said system to said tank, each valve being automatically operable upon a deficiency of fluid in its side of the system, and a third valve in said casing for connecting the sides of said system together and to said tank.

4. In a telemotor system, the combination with an operating telemotor, of an operated telemotor, a valve casing connected to the sides of said system, a storage tank connected to said casing, valves automatically operable to connect said tank to the sides of said system, whereby the formation of the vacuum in said system may be avoided, and a valve for connecting the sides of said

system and said tank independently of said first-mentioned valves.

5. A valve casing having a central passage terminating in ports adapted to be connected, respectively, to the sides of a fluid system, a main valve for opening and closing said passage, said casing having a chamber opening into said passage on opposite sides of said main valve, and auxiliary valves for normally closing said openings but movable into an open position when a predetermined decrease in pressure occurs at said port openings, said chamber having an additional port adapted to be connected to a supply tank, said main valve being also adapted to connect said chamber to said passage independently of said auxiliary valves.

JOHN E. FARRAND.
